UNITED STATES PATENT OFFICE.

ANTOINE GHIS ALBERTI AND AUGUSTE BLAISE BARON, OF PARIS, FRANCE.

SLICING-MACHINE.

1,369,600.

Specification of Letters Patent. Patented Feb. 22, 1921.

Application filed December 17, 1919. Serial No. 345,648.

To all whom it may concern:

Be it known that we, ANTOINE GHIS ALBERTI, of 2 Quai de la Rapée, Paris, France, manufacturer, and AUGUSTE BLAISE BARON, of 155 Boulevard de Magenta, Paris, France, engineer, have invented Slicing-Machines, of which the following is a clear, full, and exact description.

This invention has for its object a machine more particularly adapted for cutting ordinary meat, sausage, ham, etc., into slices of determined thickness which may be varied at will, but the said machine may also be used for cutting into slices eatables and other like products.

The improved slicing machine is essentially characterized by a frame carrying the circular knife, the to-and-fro motion of which produces the rotation of the knife and determines the forward movement of a carriage carrying the product to be cut in slices.

The knife carrying frame acts, for that purpose, on the actuating members of the carriage carrying the product to be cut, in such a manner that upon each return movement of this frame, the carriage is moved forward according to a distance corresponding to the desired thickness of the slice, which is then cut during the following forward movement of the said frame.

The accompanying drawings illustrate, by way of example only, a slicing machine made according to this invention.

Figure 1 is a front view of the upper portion of a machine embodying the invention, a portion of the frame being in section to show more clearly the feed mechanism and the parts intimately associated therewith.

Fig. 2 is a top plan view of the machine.

Fig. 3 is a sectional detail on the line 3—3 of Fig. 1.

Fig. 4 is a fragmentary view showing more clearly the working parts.

Fig. 5 is a sectional detail of a portion of the machine on the line 5—5 of Fig. 3.

Fig. 6 is a front view of the machine on a reduced scale.

As shown in the drawings, the improved machine comprises a base or frame *a* composed of two vertical cheeks and supporting a second transverse frame *b* in which can slide the carrier *c* supporting the circular knife *d*.

This carrier *c* supports, moreover, a

toothed wheel *e* loose on an axis *e* and gearing, on the one hand, with a rack *f* arranged at the upper part of the transverse frame *b* and, on the other hand, with a pinion *g* integral with the circular knife *d*.

It results from this arrangement that, when the carrier *c* is moved longitudinally in the frame, as will be explained hereafter, the fixed rack *f* produces the rotation of the pinion *e* which controls the pinion *g* and, consequently, the circular knife *d* the axis *d* of which turns freely in the carrier *c*.

As the diameter of the wheel *e* is much greater than that of the pinion *g*, it results therefrom that this pinion and the knife *d*, with which it is integral, are driven with a speed of rotation much greater than that of the toothed wheel *e* and that the products are thus easily cut into slices.

The shaft *d* of the knife *d* carried as above mentioned by the carrier *c* serves, in the example illustrated, as rocking axis for a connecting rod or link *h* the forked end of which is hinged to a lever *I* carrying at its upper part a driving handle *i* and pivoting, at the opposite end, on an axis *j* carried in a yoke *j* secured to the frame *a*.

It will therefore be seen that by imparting to the lever *i* a backward movement and then a forward movement, the carrier *c* and the knife *d* supported by the latter are moved either forward or backward and that at the same time this knife receives a rotary movement sufficient for allowing to easily cut in slices the most resistant edible product or the like placed on the carriage *k*.

The mechanism for moving forward this carriage as well as the device allowing to regulate the thickness of the slice to be cut are inclosed between two cross-pieces *l* arranged between the cheeks of the frame *a*.

This carriage *k* is so mounted as to be able to slide between the cheeks of the frame *a* on a plate *a* of less width than the interval separating the said cheeks and it is actuated in the following manner:

The carriage *k* is connected, at each of its ends, by bolts *k* passing freely through the empty spaces between the table *a* and the cheeks *a* to a counter-plate *23* at the lower part of which is secured the driving cable *o* one of the ends of which is attached to a stretching device *p* allowing to adjust the tension of the said cable.

This cable *o*, inclosed in a suitable casing, passes on a roller *9*, then on the guide rollers

r and winds on a drum s which carries, on one of its faces, a ratchet wheel t.

The intermittent actuation of the ratchet wheel t and, consequently, the forward movement, also intermittent, of the carriage k supporting the product to be cut, are obtained in the following manner:

A rod u is mounted in the frame b so as to be able to move longitudinally in the latter; this rod carries, for that purpose, at one of its ends, a heel piece u¹ which is guided in a slide b¹ of the frame b and held against the rear face of the knife carrier c by a spring u², as shown in Fig. 4.

On the other hand, this rod u carries, at the end opposite to the heel piece u¹, a pawl u³ which is held in contact with a ratchet wheel t integral with the drum s of the cable o.

It results from this arrangement that, each time the carrier c is moved backward again, after cutting a slice of the product, its rear face comes in contact with the heel piece or abutment u¹ of the rod u which is then moved backward as well as the pawl u³ carried by the latter.

This pawl then actuates the drum s, through the medium of the ratchet wheel t and thus causes the carriage k to move forward according to a length the value of which is determined by the stroke allowed to the abutment u¹ and which may be adjusted at will as will be explained hereafter.

The actuating pawl u³ rocks and is carried by the end of a tube u⁴ secured in another tube u⁵, in which can slide the rod u.

The returning spring u² normally tends to move forward the tube u⁵ and pawl u³; this spring u² is attached, on the one hand, to a fixed point l¹ of the cross-piece l and, on the other hand, to a stud u⁶ secured to the tube u⁵ and capable of moving in a horizontal slot l² of the said cross-piece (Fig. 4).

The rod u carrying the projection u¹ and arranged in the tube u⁵ is surrounded by a shock-absorbing spring 14 taking a bearing, at one of its ends, on the bottom of the tube u⁵ and, at the opposite end, against a screw or abutment u⁶ integral with the rod u and projecting in slots u⁷ made in the tube u⁵.

It results from this arrangement that, when the tube u⁵ is stopped in its backward movement by the engagement of the stud u⁶ with an adjustable stop rod 15, the pawl u³ actuating the carriage k is also held stationary and that the remainder of the return movement of the knife-carrier c produces no longer the actuation of the rod u and the compression of the shock-absorbing spring 14 in the tube u⁵.

When the carrier c is again moved forward for cutting a new slice, the projection u¹ is released, so that the whole of the rod u, tube u⁵ and pawl u³ moves forward under the action of the returning spring u².

The movement of the tube u⁵ is limited in this direction by the projection u¹ which strikes against the bottom of a slot b² formed in the lower part of the fixed frame b.

The rocking pawl u³ is connected to the retaining pawl z by a coil spring 16 holding the said pawl z in engagement with the ratchet wheel t and the rocking pawl u³ in suitable position for moving the said ratchet wheel.

The retaining pawl z, which rocks freely on an axis z¹ carried by the cross-piece i is also held in contact, by the spring 16, with a cam 17 fast on an axis 18 and provided with a small operating lever 19 which can take the positions I and II (Fig. 1), so as to release the ratchet wheel t from the retaining pawl z, when the meat-carrying carriage is to be brought backward.

The cross-piece l is perforated, in addition to the opening l², for guiding the stud u⁶, with an orifice l³ allowing the passage of a cable o winding on the drum s, passing on the rollers r and the roller 9 and attached to tension shackles p.

The adjustment of the thickness of the slices is obtained by means of the stop rod 15 sliding through the cheeks a and in a suitable slide b³ of the transverse frame b, as well as in an opening a², of one of the cheeks a (Fig. 4).

This rod 15, the end of which is arranged opposite to the stud u⁶, terminates at its other end by a projection or heel 17 which allows of moving it by hand forward and backward according to the desired thickness of the slice to be cut. This rod is provided, for that purpose, with a number of notches 18 which indicate, according to the position they occupy near the slide 19, the thickness chosen 105 corresponding to a greater or less spacing apart of the end of the rod 15 and the stud u⁶ integral with the tube u⁵.

It will be seen, by referring to Fig. 4, that the adjustment of the interval separating the rod 15 and the stud u⁶ allows of varying the backward stroke of the tube u⁵ and pawl u³ and, consequently, the value of the driving movement of the ratchet wheel t and drum s controlling the carriage k; a greater 110 or less forward movement of the product to be cut opposite the knife is thus produced, the compression of the spring 14 deadening the shock of the knife-carrier c and thus allowing it to terminate its movement without moving the pawl u³ beyond the desired point.

When the rod 15 has been brought to the required position, that is to say in one of the notches 18 opposite the edge of the slide 125 19, this rod 15 is held stationary by means of a screw 20 (Fig. 4).

The displacement of the product to be cut, arranged on its carriage, is effected in the following manner:

A carriage 21 is mounted, so as to be capable of sliding between the cheeks of the frame *a*, on a plate *a*¹ of less width than the interval separating the said cheeks. It is connected, on each of its edges, by bolts 22 passing freely through the slots *a*³ B between the cheeks *a* and the plate *a*¹, to a counter-plate 23 to the lower part of which is attached the driving cable *o*, the ends of which are secured to tension shackles *p* allowing to adjust the tension of the said cable.

It will therefore be understood that, according to the direction of the movement imparted to the cable, the carriage 21 will be moved forward or backward on the plate *a*¹.

This carriage supports, on its two vertical sides, two slides 24 adapted to receive the vertical posts 25 of a second carriage *k*, called "meat carrying carriage."

A second carriage which is rendered integral with the first carriage simply by the engagement of its posts 25 in the vertical slides 24 of the first carriage, is therefore readily removable, so that it is possible to replace it at will by another similar carriage supporting another product to be cut.

This product, meat or the like, is held in place on the meat carrying carriage by means of a plate 26, of sufficient weight, sliding with a slight friction on the posts 25 and provided, on its lower face, with points 27 entering in the meat, the said carriage *k* being provided for the same purpose, on its upper face, with retaining points 28 also entering into the meat.

The apparatus is completed by a covering plate 29, arranged on the cheeks *a* and in front of the slide *b*¹, the cheeks being, on the other hand, suitably spaced apart by the cross-pieces 30 and 31, on the last of which is mounted the roller 9 of the cable *o*.

The above described machine is more particularly intended to cut in slices edible products such as meat, bread, etc., but it is obvious that it may be used such as it is described, or with slight detail modifications, for cutting in slices any product whatever.

The constructional arrangements are given only by way of example; the forms, materials, dimensions, as well as the accessory devices may be varied without departing thereby from the nature of the invention.

The knife, for instance, might be replaced, in certain cases, by a circular saw.

The machine is mounted upon a table or stand 11 as indicated most clearly in Fig. 6. This stand or table which is readily portable must in practice be held stationary during the operation of the machine. For this purpose it is provided with a pedal 12 having teeth on its inner face and it is mounted in such a manner that when the foot presses

upon the pedal the teeth bite or engage the surface thereby holding the machine in adjusted position. A spring 13 co-operates with the pedal 12 so as to automatically disengage the latter from the surface when the pressure of the foot is removed therefrom.

Claims.

1. A cutting machine, comprising an article carrier, a cutter mounted to reciprocate across the path of movement of the article carrier, an intermittent feed mechanism for the article carrier including a ratchet mechanism, a movable stop element controlling the pawl of the ratchet mechanism and operated by the cutter, and an adjustable element for limiting the movement of said stop element.

2. A cutting mechanism, comprising an article carrier, a cutter mounted to reciprocate across the path of movement of the article carrier, a drum, a flexible connection between the drum and article carrier, a ratchet mechanism for intermittently actuating the drum, a stop element operable by means of the article carrier, yieldable connecting means between the stop element and the ratchet mechanism, and adjustable means for setting and limiting the movement of the said stop element to regulate the feed of the article carrier.

3. A machine for cutting meat and other products, edible or not, into slices, comprising a fixed longitudinal frame,—a carriage mounted on the said frame and carrying the product to be cut,—a transverse frame integral with the longitudinal frame,—a knife-carrier sliding in the said transverse frame,—a circular knife mounted in the said knife-carrier,—a hand driving lever pivoting on the fixed longitudinal frame,—a crank rocking on the said lever and on the axis carrying the circular knife so as to impart to the latter a double movement of translation transversely to the product to be cut,—means for producing the rotation of the circular knife and the adjustable and intermittent forward movement of the carriage carrying the product to be cut.

4. A slicing machine comprising a fixed longitudinal frame,—a carriage mounted on the said frame and carrying the product to be cut,—a transverse frame integral with the longitudinal frame,—a rack integral with the transverse frame,—a knife-carrier sliding in the said frame,—a circular knife in the said knife-carrier,—a pinion integral with the said knife,—a toothed wheel carried by the knife-carrier, this wheel gearing with the pinion integral with the circular knife and with the fixed rack so as to produce, upon the forward and backward displacements of the knife-carrier, the rotation of the circular knife,—means for producing the intermittent forward movement of the carriage carrying the product to be cut and

- for regulating at will the intermittent displacement of the said carriage as well as the thickness of the slices to be cut.
5. In a slicing machine, a fixed longitudinal frame,—a carriage mounted on the said frame and carrying the product to be cut,—a driving cable attached at its free ends to the said carriage,—a drum on which winds the said cable, this drum being mounted between the cheeks of the longitudinal frame,—a ratchet wheel integral with the said drum,—a rod carried by the longitudinal frame and capable of sliding in the said frame,—a heel piece integral with this rod,—a spring attached to the said rod and to the frame for maintaining the heel piece in contact with the knife-carrier, a driving pawl mounted at the end of the sliding rod, so as to actuate the ratchet wheel at each backward movement of the knife-carrier,—a retaining pawl preventing the backward movement of the said ratchet wheel,—means for regulating the forward return movement of the pawl-carrying rod and, consequently, the actuation of the ratchet wheel and of the carriage carrying the product to be cut.
6. In a slicing machine as above, a member for regulating the stroke of the rod carrying the pawl controlling the displacement of the carriage receiving the product to be cut, the said member comprising a rod slidably mounted in the longitudinal frame,—an abutment carried by this rod opposite the pawl,—notches on the said rod,—a spring holding these notches in engagement with a stop on the frame,—a manipulative knob allowing the longitudinal displacement of the regulating member opposite the driving pawl and limiting the stroke of the latter as well as the forward movement of the carriage carrying the product to be cut,—the said device allowing to vary at will the thickness of the slices to be cut and acting on the retaining pawl for releasing the said carriage and bringing it backward.

7. In a slicing machine as above, a carriage supporting the product to be cut, comprising a vertical post forming a rack,—a second vertical post perforated with holes,—a cross-bar pressing on the product to be cut, engaging with the rack of one of the posts and held on the other by means of a key,—teeth or projections on the carriage and on the cross-bar for preventing the displacement of the product on the said carriage.

8. In a slicing machine, a modification of the device controlling the intermittent actuation of the carriage carrying the product to be cut, comprising a tube,—a driving pawl rocking at one end of this tube,—a rod capable of sliding in the said tube,—projections on the said rods, engaging in slots made in the tube,—a spring arranged between the bottom of the tube and the projections of the sliding rod,—a heel piece at the end of this rod, this heel piece being engaged in a guide slot of the transverse frame and held by the spring fitted in the bottom of the said slot or against the rear face of the knife-carrier.

9. In a slicing machine as above, a device for regulating the thickness of the slices, comprising a stop rod sliding in a guide of the transverse frame,—notches in the said rod,—a screw projecting in one of the notches,—an operating handle on the said stop rod for bringing the latter in any suitable position opposite a projection of the pawl-carrying tube for limiting the stroke of said projection and, consequently, the actuation of the ratchet wheel and of the carriage carrying the product to be cut.

The foregoing is a specification of our slicing machine, more particularly adapted for cutting eatables into slices, signed by us, this 5th day of November, 1919.
